Patented Feb. 4, 1919.

UNITED STATES PATENT OFFICE.

WILLIAM E. MOORE, OF PITTSBURGH, PENNSYLVANIA.

ELECTRIC METALLURGICAL FURNACE.

1,293,164.

Specification of Letters Patent.

Patented Feb. 4, 1919.

Application filed July 30, 1917. Serial No. 188,567.

To all whom it may concern:

Be it known that I, WILLIAM E. MOORE, a citizen of the United States, residing at Pittsburgh, in the county of Allegheny and 5 State of Pennsylvania, have invented certain new and useful Improvements in Electric Metallurgical Furnaces, of which the following is a specification.

This invention relates to improvements in 10 metallurgical furnaces, and one of its objects is to provide a furnace which shall combine advantageous features of both the induction type and the arc type of electric furnace.

15 To start an induction furnace, say of the kind employing a loop of metal which passes around the inductive element, it is necessary to first fill the chamber of this loop with molten metal which, according to the present practice, is obtained from a fuel or other furnace. My invention overcomes the necessity for obtaining molten metal from some outside source such as referred to, by introducing into the metal chamber of the induction furnace one or more electric arcs which may be used initially to melt a sufficient amount of metal to fill the induction loop or loops, after which the arc may or 25 may not be used.

20 On the other hand, in arc type melting furnaces, it is desirable to have a portion of the heat produced by one or more submerged inductive loops, which have the effect of producing a vigorous circulation of 35 the bath and effecting thereby an agitation especially desirable in the purification and manufacture of high grade and alloy steel in order to dissolve the alloys.

The invention has for its further object 40 the provision of an induction furnace wherein the "pinch" effect shall be reduced to a minimum.

In order to more fully describe my invention, reference will be had to the accompanying drawings, wherein:

Figure 1 represents in vertical section a furnace embodying one specific form of my invention;

Fig. 2 is a section taken on the line 2^x—2^x 45 of Fig. 1; and

Fig. 3 is a detail fragmentary section of the modification of the inductive loop.

The furnace here shown comprises, among other parts, a roof 1, side walls 2 and bottom 55 3, all of any suitable refractory material. The bottom 3 has two extensions 4 and 5

which project downwardly from the bottom proper at an angle, as shown. These projections are pierced, respectively, by openings 6 and 7 causing the extensions to form two 60 loops. In these loops are formed, respectively, channels 8 and 9, each channel following the arc of a circle at the lower end of the loop, and gradually expanding or tapering upward where it merges into the chamber 65 proper of the furnace. In cross section, these channels are oval-shaped, as shown in Fig. 2. They may, however, be of rectangular shape in cross section, as shown, for example, at 9' in Fig. 3.

70 The openings 6 and 7 receive coils 10 and 11 wound on cores 12 and 13 provided, respectively, with laminated yokes 14 and 15, the inner walls of the extensions 4 and 5 being struck on the arc of a circle for about 75 180° to conform to the contour of the coils, and the channels 8 and 9 are concentric for the angular distance above-mentioned with said inner walls.

Extending vertically through the roof of 80 the furnace are three arcing electrodes 16, 17 and 18, connected to a suitable source of three-phase alternating current, indicated by the transformer secondary 19. It is understood that any suitable means may be employed for supporting and imparting vertical movement to these electrodes.

85 The heating coils 10 and 11 are excited from two separate transformers 20 and 21 on a two-phase circuit. If only a single 90 heating coil is employed, a single-phase current would suffice. If three heating coils are employed, each would receive current from a different leg of a three-phase circuit, and so on.

95 With the construction shown, considerable hydrostatic pressure is maintained on the molten metal within the inductive loops, thereby greatly reducing the action known as the "pinch" effect which tends to pinch 100 off or rupture the stream of molten metal when forced to the high current densities necessary for rapid heating. The "pinch" effect is due to the constriction of the fluid stream by the magnetic forces circulating 105 perpendicularly to the axis of current flow, is proportionate to the square of the current, is resisted by hydrostatic pressure, and is reduced when the stream is of oval or elongated in section, due to the fact that the 110 lines of force on opposite sides of the stream tend to neutralize each other by being

brought closer together than would be the case were the stream square or circular in cross section. My invention takes advantage of these ways of reducing the "pinch" effect.

Also due to the magnetic repulsion radially from the inductive cores, the outer layers of metal in the inductive loops tend to be forced upward and outward, and are replaced by metal flowing down the inner sides of the loops. This causes a motive effect which results in rapid circulation of the metal. For the purpose of facilitating this action, the loop channels 8 and 9 gradually expand as they extend upward into the main chamber of the furnace.

The refractory material of the inductive loops is reinforced on the outside by a metallic casing 22, cut or split, as at 23, to interrupt the electrical circuit formed by it.

While I have herein shown and described one specific embodiment of my said invention, it will be understood that the same may be modified in various ways without departing from the spirit thereof.

Having thus described my invention, what I claim as new and desire to secure by Letters-Patent is:—

1. An electric metallurgical furnace comprising a chamber or crucible adapted to contain metal, means for heating the metal therein by an electric arc, an extension formed on the furnace bottom projecting downwardly therefrom to form a loop and having a loop channel therein communicating with the main chamber, and an electrical heating element in inductive relation to the metal in said loop.

2. An electrical metallurgical furnace comprising a chamber adapted to contain metal, means for heating the metal in said chamber by an electric arc, an extension formed on the furnace bottom projecting downwardly therefrom to form a loop and having a loop channel communicating with the main chamber at the upper ends of the loop, and an electrical heating element in inductive relation to the metal in said loop, the upper ends of the loop gradually expanding upwardly from a point substantially midway of the heating element to the point of communication of the ends of the loop with the main chamber.

3. An electrical metallurgical furnace comprising a chamber adapted to contain metal, means for heating the metal in said chamber by an electric arc, an extension formed on the furnace bottom projecting downwardly therefrom to form a loop and having a loop channel communicating with the main chamber at the upper ends of the loop, and an electrical heating element in inductive relation to the metal in said loop,

the upper ends of the loop gradually expanding upwardly from a point substantially midway of the heating element to the point of communication of the ends of the loop with the main chamber, said channel being elongated in transverse section.

4. An electrical metallurgical furnace comprising a chamber adapted to contain metal, means for heating the metal in said chamber by an electric arc, an extension formed on the furnace bottom projecting downwardly therefrom to form a loop and having a loop channel communicating with the main chamber at the upper ends of the loop, and an electrical heating element in inductive relation to the metal in said loop, the upper ends of the loop gradually expanding upwardly from a point substantially midway of the heating element to the point of communication of the ends of the loop with the main chamber, said channel being elongated in transverse section, and being substantially U-shaped in longitudinal section, the central axis of said U-shaped channel being inclined to the vertical.

5. An electrical metallurgical furnace comprising a chamber adapted to contain metal, an electric arc disposed in the upper part of the chamber for heating the metal therein, a pair of extensions formed on the furnace bottom, said extensions being angularly disposed with respect to each other and to the central vertical axis of the furnace, each of said extensions having a channel in the form of a loop, said channels being of elongated transverse section and gradually expanding upwardly toward their upper ends and being in communication with said main chamber, and an electrical heating element around which each extension is looped.

6. An electric metallurgical furnace comprising a chamber or crucible adapted to contain metal, an extension formed on the furnace bottom projecting downwardly therefrom to form a loop and having a loop channel therein communicating with the main chamber, and an electrical heating element around which said extension is looped, said channel gradually expanding upward.

7. An electric metallurgical furnace comprising a chamber or crucible adapted to contain metal, an extension formed on the furnace bottom projecting downwardly therefrom to form a loop and having a loop channel therein communicating with the main chamber, and an electrical heating element around which said extension is looped, said channel being substantially U-shaped in longitudinal section, elongated in transverse cross section, and gradually expanding upward.

In testimony whereof I affix my signature.
WILLIAM E. MOORE.
